(57) **CLAIM**

We claim the ornamental design for a clipper head, as shown and described.

DESCRIPTION

FIG. 1 is a top plan view, of a clipper head showing our new design;

FIG. 2 is a bottom plan view thereof;

FIG. 3 is a right side elevation view thereof;

FIG. 4 is a left side elevation view thereof;

FIG. 5 is a front elevation view thereof;

FIG. 6 is a rear elevation view thereof;

FIG. 7 is a first perspective view thereof; and,

FIG. 8 is a second perspective view thereof.

1 Claim, 6 Drawing Sheets
